UNITED STATES PATENT OFFICE.

NICOLAS KRIBS, OF DUNDEE, ILLINOIS.

BATTERY-LAMP.

1,197,131.

Specification of Letters Patent. Patented Sept. 5, 1916.

Application filed January 15, 1916. Serial No. 72,215.

To all whom it may concern:

Be it known that I, NICOLAS KRIBS, a citizen of the United States, residing at Dundee, in the county of Kane and State of Illinois, have invented certain new and useful Improvements in Battery-Lamps, of which the following is a specification.

My present invention relates, in part, to battery lamps or lanterns, of the type disclosed in an application for Letters Patent, Serial No. 26,945, filed by me on the 10th day of May, 1915, Patent No. 1,168,892, January 18, 1916, and it embodies improvements thereon, and the said invention also relates to improvements in batteries, whether the same are designed for use for lamps or lanterns of the above mentioned or portable type, gas engine ignition, or other purposes, and it consists in certain peculiarities of the construction, novel arrangement and operation of the various parts thereof, as will be hereinafter more fully set forth and specifically claimed.

The objects of the present invention include those set forth in my said application for patent and those objects or advantages attained by the novel construction, arrangement and operation of the various parts as therein set forth, and in addition thereto has as a further object to provide simple and efficient means for fixing or firmly holding the lamp-carrying casing in any position to which it may be turned.

A further and important object is to provide means for connecting a plurality of dry cells in series, to obtain an increase of voltage, within the space occupied by a single dry cell, and in such a manner that the cells will be effectively and electrically secured together, so that they can be readily placed in or removed from a carton or casing, as a unit, and so that they will not be disconnected by jarring, shocks, or vibrations.

Still another important object of the present invention, is to furnish means for firmly or rigidly and electrically (if desired,) connecting one of the cells to a container, to the end, that the cells will always be held in positive contact with one another and prevent displacement with respect to the container.

Other objects and advantages of the invention will be disclosed in the subjoined description and explanation.

In the accompanying drawings, which

serve to illustrate an embodiment of the invention, Figure 1 is a view in side elevation of a lamp or lantern embodying my improvements. Fig. 2 is a vertical sectional view thereof, taken on line 2—2 of Fig. 1 looking in the direction indicated by the arrows. Fig. 3 is an enlarged sectional view taken on line 3—3 of Fig. 1 looking in the direction indicated by the arrows, showing the construction of the rotary support for the lamp, whereby the position of the latter may be changed so as to direct the rays of light in different directions, and illustrating the means for fixing the rotary support in any desired position. Fig. 4 is a similar view to that shown in Fig. 2 but illustrating a modified form of the lamp. Fig. 5 is a view partly in section and partly in elevation of the lamp illustrating another modification in the construction thereof. Figs. 6 and 7 are views partly in section and partly in elevation of battery cells illustrating modified means in the manner of connecting said cells together so as to form a unit, and also illustrating means for securing the lower cell to a container therefor. Fig. 8 is an enlarged sectional view taken on line 3—3 of Fig. 1 looking in the direction indicated by the arrows showing a modification in the manner of mounting the rotary support for the lamp, on the standards or brackets therefor. Fig. 9 is a detached perspective view of a securing member or nut used on one of the battery cells as shown in Figs. 2 and 11 for receiving a screw threaded projection mounted on the upper portion of the carbon of the lower cell. Fig. 10 is a view partly in section and partly in elevation of a pair of battery cells showing another modification in the means of connecting them together and Fig. 11 is a fragmental view partly in section showing the securing member illustrated in Fig. 9 secured to the bottom of one of the cells of a battery.

Corresponding numerals of reference, refer to like parts throughout the different views of the drawings.

The reference numeral 10 designates a container for the dry battery cell or cells, and said container is by preference cylindrical in shape and made of metal and may have attached to its walls a handle 11 used for carrying the device or to direct the rays of light from the lamp, mainly in a horizontal direction. Pivotal secured to the

upper portion of the walls of the container 10 and diametrically opposite each other, are the ends 12 of the bail or handle 13 which can be used for carrying the device 5 as a lantern. The lower end of the container is permanently closed and is provided with a depression or cavity 53, that is to say, the lower end of the container 10 is upwardly or inwardly depressed in such a way 10 as to form an internal channel between the inner wall 54 of said depressed portion and the lower extremity of the wall of the container, thus forming an annular groove 55 for the reception of the lower end of the 15 carton, and the lower end of the lowermost battery cell, the construction of both of which will be presently explained. The upper end of the container is closed by means of a cap or cover 14 which is snugly fitted 20 to said upper end. Mounted on the upper surface of the cap or cover at a suitable distance apart, are a pair of upright standards 15 and 16 which are made of metal and said standard 16 has in its upper portion an 25 opening 17 for the reception of one end of a bolt 18, which has its outer portion screw-threaded for engagement with a nut 56, said bolt and nut being employed for the purposes to be presently explained. The upper 30 portion of the standard 15 has in its upper part an opening 19 into which projects through a suitable opening 20 near one end of a bracket 21, a pin 57 on the block 30, which bracket is connected at its other end 35 to the rear portion of the lamp casing 22, which casing is substantially concavo-convex in shape and has fitted thereon in any suitable manner, a similarly shaped reflector 23, and said casing may have its front end 40 closed by means of a glass plate 24 secured thereon or thereto in any suitable way. The rear or reduced portion of the casing 22 is provided with a hollow neck or extension 25 to receive a lamp socket 26, which is of the 45 ordinary incandescent type and carries a bulb 27 which is located centrally within the reflector 23 and has within the same a filament 28 as is clearly shown in Fig. 3 of the drawings.

50 Rotatably mounted between the bracket 21 and the upper portion of the standard 16 is a block of insulating material 30 which is by preference cylindrical in shape, and has on its outer portions, adjacent to the casing 55 22 a socket 31 in which the extension 25 of the casing 22 is fitted. Extended transversely through the block 30 is an opening 32 for the reception of an adjustable screw 33 which carries on its inner end a spiral 60 spring 34, which spring has on its free end a contact piece 35 of metal to contact with the part 29 of the lamp. The screw 33 extends through the transverse opening 36 in the rod 18 which, as shown in Fig. 3 has on 65 its outer portion a disk 37 to rest between

the upper portion of the standard 16 and the adjacent end of a washer 30^a and is electrically connected to the screw 33 and lamp. The washer 30^a has on its central portion, opposite the disk 37, a sleeve or reduced 70 portion 38, to fit in an opening in a bracket 39 which is connected to the casing 22, as is clearly shown in Fig. 3 of the drawings, and is interposed between one end of the block 30 and said washer. 75

Referring now to Fig. 2 of the drawings, it will be seen and understood that the container 10 has located therein, one above the other, two battery cells 40 and 41, which may be of the ordinary 1½ volt type and construction, except that the lower end of each cell, but more particularly the lower cell is provided with an annular and outwardly extended rim or flange 58 thus forming an upwardly extended depression 59 of a size and shape to correspond with and to fit on the upper surface of the depression 53 in the container. By so constructing the cells 40 and 41, especially the latter, it is obvious that the annular flange 58 will fit in the 90 groove between the wall 55 of the depression 53 and the lower extremity of the wall of the container 10, and that the flange 58 of the cell 40 will be located at a distance from the upper end of the cell 41, and maintained 95 in such position by means of the nut on the bottom of the cell 40, and the projection 62, engaging therewith, which nut and projection are interposed between the two said cells. The bottom of the carton 60, for said 100 cells is removed to expose the zinc bottom of the lower cell, to the end, that electric connection may be easily and effectively made between the bottom of the lower cell 41, and the bottom of the container. 105

In order to effect the aforesaid connections, the zinc bottom of the lower cell 41 is provided centrally with a depending screw-threaded stud 43 which is extended through a suitable central opening in the bottom of the container 10 and has mounted on its lower portion a nut 61, which, when tightened up on the stud 43 will firmly hold the lower cell 41 in contact with the bottom of the container 10 and snugly within the walls 110 of the latter. The carbon 42 of the lower cell 41 is provided with a screw-threaded projection 62 to engage an opening 63 in a member 64, see Figs. 2, 9 and 11. Said member is made of metal and is secured to 115 the zinc bottom of the cell 40 outwardly of the center thereof, but so that the opening 63 of said member will be located centrally with respect to said cell bottom. It will be observed by reference to the last mentioned 120 figures of the drawings, that the member 64 is provided with an off-set or shoulder 65 and an extension 66, which extension may be secured to the bottom of the cell 40 by means of solder or otherwise. Leading from 125

the binding post 44 of the upper part of the cell 40, is a conductor 45 which is connected to one end of a switch 46, which is insulated from the cap or cover 14 but mounted thereon as is clearly shown in Figs. 2 and 4 of the drawings. This switch may be of any suitable kind, but in the present instance, it is shown as being a spring switch, capable of being depressed 10 into contact with a post 47 mounted on the cover or casing 14 but insulated therefrom. The post 47 has connection through a conductor 48 and a post or screw 49 with a standard 16 as will be readily understood by reference to Figs. 2 and 4 of the drawings.

In Fig. 4, is shown a modification in the construction of the lamp, which consists in using a single battery cell 50 instead of a pair of superimposed cells as above described. In this modified construction, the cell 50 at its lower portion, is of the same construction as the cell 41 above set forth and described, and as usual, is surrounded by a carton 60, the bottom of which is removed so that the zinc bottom of the cell 50 will be exposed. In this modified construction the zinc bottom of the cell 50 is provided with a screw-threaded stud 43 to extend through an opening in the bottom of 25 the metallic container 10 as in the above described construction, and said cell and container are connected together by means of a nut 61 screwed onto the stud 43 so as to clamp the cell 50 and container together 30 and in electric connection with one another. The upper portion and conducting parts leading from the battery to the lamp are the same as previously described.

In Fig. 5 of the drawings is shown another modification in the construction of the lamp, which consists in employing two cells 40 and 41 located in the container 10 and both surrounded by a single carton 60, and each having its zinc bottom exposed. In 45 this construction, the container is constructed as shown and described in Figs. 2 and 4 of the drawings, and the cells 40 and 41 are constructed as shown and described with reference to said figures, except that the carbon 42 on the upper end of the lower cell is provided with a screw threaded projection or stud 62 which engages an opening in a nut 67 which is centrally secured to the zinc bottom of the upper cell 40 of the battery.

In Fig. 8, is shown a modification in the construction of the rotary support for the lamp which is of identical construction, as that shown in Fig. 3, with the exception 60 that the rod 18 is extended entirely through the block 30, instead of being extended only partially through said block, as shown in Fig. 3, and has on its end opposite that end thereof on which the adjusting nut 56 is mounted, a head 68 which rests against the

outer portion of a sleeve 69 of insulating material which surrounds the rod 18 and is located in the openings 19 and 20 of the parts 15 and 21, respectively, which are made sufficiently large to receive said insulating sleeve.

As my improved battery is adaptable for use other than for portable lamps, I have shown in Figs. 6 and 7, 10 and 11, portions of cells of a battery without any container therefor, and have illustrated in Fig. 6 one form or means for uniting a plurality of cells in one manner, in Fig. 7 a plurality of cells in another manner and in Fig. 10 a plurality of cells in another manner, in each of which figures is also illustrated means for connecting the lower cell to a container or support.

In the construction illustrated in Fig. 6 the bottom of the cell 41 is constructed in the same manner as the cells 41 and 50 and as above described, that is, said cell has on its bottom a centrally located screw-threaded stud 43 to engage a nut or support, not shown, and the upper end of said cell has extended from its carbon 42 a screw-threaded stud 62 which engages an opening in a nut 67 centrally secured to the bottom of the cell 40, which latter cell has extended from its carbon 42 a screw threaded projection or stud 44 which may engage or have connection with an electric conductor, or another cell, if desired.

In Fig. 7, the modification consists in employing a spring or resilient connection 68 which is connected at one of its ends to the bottom of the cell 40 and at its other end to the carbon 42 on the upper portion of the lower cell.

The modification shown in Fig. 10 consists in a flexible connection 69 which is secured at one of its ends to the carbon 42 on the upper portion of the lower cell and at its other end to the bottom of the cell 40 located adjacent thereto.

From the foregoing and by reference to the drawings, it will be readily understood and clearly seen, that by employing the improvements hereinbefore set forth, the lamp carrying casing 22 may be readily adjusted 105 to any desired position by means of its rotary support, when by tightening the nut 56 on the rod 18, it may be fixed or firmly secured in the desired position. It is also obvious that my present improvements afford means for uniting a plurality of dry cells, one with the other, so that they may be handled or placed in a container, or removed therefrom, as a unit, and also in such a manner that when they have been placed in the container, they will be firmly, if not rigidly secured therein, so as to withstand shocks and jars in the shipment or handling thereof, as well as, to the end, that their connections will not be broken or disarranged 110 115 120 125 130

by vibrations to which the battery may be subjected, especially if the same is used for gas engine ignition on automobiles, motor-boats, and for like purposes.

5 The form of the receiving member 64, is of especial advantage in that it can be very easily soldered to the battery cell and at the proper point on the bottom thereof, as will be obvious to anyone skilled in the art to 10 which the invention pertains.

What I claim is—

1. In a device of the character described, the combination with a container having one of its ends open, of a cover for said end, an 15 electric generator located within the container and electrically connected thereto, a pair of spaced apart standards mounted on the upper end of said container, a block of insulating material rotatably mounted on 20 and between said standards and having an opening extended transversely therethrough and another opening extended from one of its ends longitudinally therewith and intersecting the first named opening, a pair of 25 lamp carrying brackets mounted on said block, one of said brackets being in electrical contact with one of said standards and the other of said brackets being insulated therefrom, a lamp mounted on the 30 outer portions of said brackets and having a post extended into one end of said transverse opening, a rod extended through one of the standards into the longitudinal opening of said block and having a transverse 35 opening to register with the transverse opening of the block, a disk on said rod near one of its ends, a nut adjustably mounted on the outer portion of said rod to clamp one of the standards against said disk so as to fix said 40 block, a screw located in the transverse openings in said block and rod to contact with said post of the lamp, and a circuit closer for the electric generator.

2. In a device of the character described, 45 the combination with a container having one of its ends open, of a cover for said end, an electric generator within the container and electrically connected thereto, a pair of spaced apart standards mounted on the 50 upper portion of said container, a block of insulating material rotatably mounted on and between said standards and having an opening extended transversely therethrough and another opening extended from one of its 55 ends longitudinally therewith and intersecting the first named opening, a pair of lamp carrying brackets mounted on said block and extended therefrom, one of said brackets being in electric contact with one of said 60 standards and the other of said brackets being insulated from the other standard, a lamp mounted on the outer portion of said brackets and having a post extended into one end of said transverse opening, a rod 65 extended through one of the standards into

the longitudinal opening of said block and having a transverse opening to register with the transverse opening of the block, a disk on said rod near one of its ends, a nut adjustably mounted on the outer portion of 70 said rod to clamp one of the standards against said disk so as to fix said block, a screw located in the transverse openings in said block and rod, a spring actuated contact interposed between the inner end of 75 said screw and the said post of the lamp and a circuit closer for the generator.

3. In a device of the character described, the combination with a container having one of its ends open, of a cover for said end, a 80 pair of battery cells located one on the other within the container and having electric connection with one another as well as with the container, a pair of spaced apart standards mounted on the upper portion of said 85 container, a block of insulating material rotatably mounted on and between said standards and having an opening extended transversely therethrough, a pair of lamp carrying brackets mounted on said block and extended therefrom, one of said brackets being in electrical contact with one of said standards and the other of said brackets being insulated from the other of said standards, a lamp mounted on the outer portion of said 90 brackets and having a post at one end of said transverse opening, a journal for one end of said block extended from one of said standards but insulated from the bracket adjacent thereto, a rod extended through the 95 other of said standards into the longitudinal opening of said block and having a transverse opening to register with the transverse opening of the block, a disk on said rod near the last named standard, a nut adjustably mounted on the outer portion of said rod to clamp the last named standard against said disk so as to fix said block, a screw located 100 in the transverse openings of said block and rod, a spring actuated contact interposed between the inner end of said screw and the said post of the lamp, and means to open and close the electric circuit.

4. In a lamp, the combination with a container having one of its ends open, of a cover for said end, an electric generator located within the container and electrically connected thereto, a pair of spaced apart standards on said cover, a block of insulating material rotatably mounted on and between 115 said standards and having an opening extended transversely therethrough and another opening extended longitudinally therethrough and intersecting the said transverse opening, a rod extended through the said longitudinal opening and having a transverse opening and one of its ends screw-threaded and a head on its opposite end, the said rod being journaled in said standards 120 but insulated from one of them, a disk on 125

- said rod adjacent to the other standard, a nut on the screw-threaded portion of said rod, a pair of lamp carrying brackets mounted on the rod, one of said brackets being in electrical contact with one of said standards but insulated from said rod, and the other of said brackets being insulated from the other of said standards as well as from said rod, a lamp mounted on the outer portions 10 of said brackets and having a post extended into one end of said transverse opening, a screw located in the transverse openings in said block and rod to contact with said post, and a circuit closer for the electric generator.
5. In a device of the character described, the combination with a container having one of its ends open, of a cover for said end, an electric generator located within the container and electrically connected thereto, a pair of spaced apart standards mounted on the upper end of said container, a block of insulating material rotatably mounted on and between said standards and having an opening extended transversely therethrough and another opening extended from one of its ends longitudinally therewith and intersecting the first named opening, a pair of lamp carrying brackets mounted on said block, one of said brackets being in electrical contact with one of said standards and the other of said brackets being insulated therefrom, a lamp mounted on the outer portions of said brackets and having a post extended into one end of said transverse opening, a rod extended through one of the standards into the longitudinal opening of said block and having a transverse opening to register with the transverse opening of the block, a nut adjustably mounted on the outer portion of said rod to press the standard adjacent thereto toward said block, a screw located in the transverse openings in said block and rod to contact with said post of the lamp, and a circuit closer for the electric generator.
6. In a lamp, the combination with a container having one of its ends open, of a cover for said end, an electric generator located within the container and electrically connected thereto, a pair of spaced apart standards on said cover, a block of insulating material rotatably mounted on and between said standards and having an opening extended transversely therethrough and another opening extended longitudinally therethrough and intersecting the said transverse opening, a rod extended through the said longitudinal opening and having a transverse opening and one of its ends screw-threaded and a head on its opposite end, the said rod being journaled in said standards but insulated from one of them, a nut on the screw-threaded portion of said rod, a pair of lamp carrying brackets mounted on the rod, one of said brackets being in electrical contact with one of said standards but insulated from said rod, and the other of said brackets being insulated from the other of said standards as well as from said rod, a lamp mounted on the outer portions of said brackets and having a post extended into one end of said transverse opening, a screw located in the transverse openings in said block and rod to contact with said post, and a circuit closer for the electric generator.
